UNITED STATES PATENT OFFICE.

BYRON A. LITCHFIELD AND LOUIS ZIMMERMANN, OF PONTIAC, MICHIGAN.

DEVICE FOR FORMING SPRINGS.

1,105,982.

Specification of Letters Patent. Patented Aug. 4, 1914.

Application filed February 18, 1914. Serial No. 819,317.

To all whom it may concern:

Be it known that we, BYRON A. LITCHFIELD and LOUIS ZIMMERMANN, citizens of the United States, residing at Pontiac, county of Oakland, State of Michigan, have invented a certain new and useful Improvement 5 in Devices for Forming Springs, and declare the following to be a full, clear, and exact description of the same, such as will enable others skilled in the art to which it 10 pertains to make and use the same, reference being had to the accompanying drawings, which form a part of this specification.

15 Our invention relates to improvements in mechanism for the manufacture of springs, especially springs for vehicles adapted to travel upon common roads as carriages, wagons, automobiles and the like, and it consists 20 in the various arrangements and combinations hereinafter described and claimed.

In the drawings: Figure 1, is a plan view of our improved arrangement and construction with the spring blank in place adapted 25 to be shaped to its permanent form. Fig. 2, is a plan view of the same apparatus with the blank shaped upon the former block. Fig. 3, is a cross section on the line X—X of Fig. 2. Fig. 4, is a cross section on the 30 line Y—Y Fig. 2.

Similar letters refer to similar parts.

In the manufacture of springs the usual mode of shaping them is to create a former which in the apparatus we have devised is 35 shown at A, B being a blank heated to the extent of destroying its elasticity so that when it is formed, it will retain its formed shape. The former block A may be of any particular form desired for the spring. In 40 the block we have shown, the form is of the type used quite extensively in the manufacture of automobile springs. The blank B being adapted when formed to be the master leaf of the spring although it is ob- 45 vious that other and shorter blanks can be formed upon the same former A to conform thereto. The master leaf usually contains eyes at the ends e e to take attaching bolts and thereby attaching them to clips which 50 in turn are attached to axles or other supporting means.

C is a plunger adapted to be operated longitudinally in the direction of the arrow by any convenient means, as a rotating cam, 55 hydraulic press, or other equivalent means for forcing it up toward the former block

A, as shown in Fig. 2. Of course, the former block A and its support A' are held rigidly upon any convenient means of support (not shown) so that the plunger C 60 can be made to approach it to within any determinate distance.

The plunger C comprises a frame D having cross bars E E which carry slidably engaging therewith rigid stems F F of any 65 convenient number and which in turn support plunger bars G G. The bars G G themselves are in turn attached to the rods F by being counterbored, as shown in dotted lines in Fig. 4, at g and are fastened there- 70 in by set screws g' g'. By means of the set screws the bars G may be adjusted with reference to the rods F. Surrounding the rods F are strong spiral springs S S being held therein by pins S' S' passing through 75 the rods. By this means the bars G are cushioned, they being yieldingly held by the springs S S.

In addition to the bars G G we employ two heavier thrust bars H H pivoted at h h 80 upon the plunger C the pivot hole being elongated, as shown at h' Fig. 3. These bars H H are backed up preferably by bowed springs so that they also can yield in their elongated pivot holes to a certain 85 extent against any pressure brought against their outer ends. At the outer ends are journaled a pair of rollers R R. These are really friction rollers and are adapted to be brought upon the outer edges of the 90 spring blank B. The two bars H H are connected by a strong spiral spring S² so that normally when disengaged from the spring blank they are drawn toward each other thereby with considerable force bring- 95 ing together the plungers G G between them, as shown in Fig. 1. Any convenient means of attaching the spring S² to these bars H H may be used as a bolt for instance at T Fig. 4.

It is in the use of the bars H connected by the spring S² and their mode of operation; especially in regard to the forming of a spring of the form shown in the drawings that our invention more particularly 105 resides. A larger number of plungers G, G may be used than are necessary ordinarily but these accommodate longer or shorter springs and also when not impinging upon any spring, they operate as guides for the other plungers. Ordinarily the plungers G G are set upon the rods F so that their

lower ends in contour generally conform to the shape of the form spring. This adjustment is made by the set screws g' and when once set it is unnecessary to reset except a 5 new former of different shape is employed and then they are made generally to conform to that.

The operation of the device, although somewhat complicated in detail, is extremely 10 simple. Of the former shown in Fig. 1 at A the heated blank B is placed in proper relation thereto and centered by a center bolt V. While still in the heated condition the plunger head C is moved toward it, the 15 rollers R R engaging that part of the spring which is opposite the concavities or reëntering angles $a a$ on the former and bringing a pressure to bear not only directly against the former but by virtue of the connecting spring S^2 , the pressure is on converging lines thus compelling the spring blank B to take the form of the concavity $a a$. The outer ends of the bars H H being separated against the spring S^2 the rolls R R 20 rolling along the spring blank and rolling it into shape, as it were, upon the former A. The plungers G G respectively also engage the spring-leaf and press closely into shape to the former A and when so pressed it is 25 allowed to remain until the spring-leaf is comparatively cold when it sets in the form that it has been shaped to. The plunger head C carrying all these attachments is then withdrawn, the formed spring-leaf may 30 or may not be withdrawn as other and shorter leaves may be formed upon it using it as a former or it may be withdrawn and the shorter leaves forming upon the original former A if desired. It is preferable, how- 35 ever, to form the leaves corresponding to the entire spring upon one another successively as thereby their contours enlarge to conform to the enlargement required by the shape of the spring when assembled. Thus two to 40 four or five successive leaves of the entire spring may be formed one after another, each succeeding one being upon the one preceding it until the entire assembled spring is 45 complete. The leaves then are taken off, 50 heated and tempered in the usual manner.

Having thus described our invention what we desire to claim is:

1. In mechanism of the class described, the combination of a former provided with a 55 reëntering angle, a plunger, a thrust bar having a sliding and pivoting movement on said plunger, a spring for normally thrusting the thrust bar on its sliding pivot toward the

former, and means for yieldingly pulling the thrust bar to the side of a line parallel with 60 the line of travel of the plunger and toward the high side of the reëntering angle of the former.

2. In mechanism of the class described, the combination of a former provided with a reëntering angle, a plunger adapted to be reciprocated toward and away from the former, a thrust bar having a slot and pin pivoting on said plunger, a bowed spring carried on the plunger and engaging with 70 the pivoted end of the thrust bar, and a spring for yieldingly pulling the thrust bar toward the high side of the reëntering angle of the former.

3. In mechanism of the class described, 75 the combination of a former provided with reëntering angles on each side of its mid portion, a plunger adapted to be reciprocated toward and away from the former, a pair of thrust bars having a sliding and piv- 80 otting movement on said plunger on opposite side of the mid portion of the former with one thrust bar in adjacency with each reëntering angle, means for yieldingly forcing each thrust bar longitudinally toward the 85 former, and means for yieldingly connecting the two thrust bars to make them initially converge toward the mid portion of the former.

4. In mechanism of the class described, 90 the combination of a former having reëntering angles in either side of the mid portion, a plunger adapted to be reciprocated toward and away from the former, a plurality of yieldingly pressed plunger bars mounted 95 upon the plunger and yieldingly tending in the direction of the former, a pair of thrust bars having a sliding and pivoting movement to the plunger and located on opposite sides of the mid portion of the former in 100 adjacency one with each reëntering angle, the said two thrust bars being separated by a plurality of plunger bars, means for yieldingly thrusting the thrust bars longitudinally toward the former, and means for 105 yieldingly causing the thrust bars to initially converge, each bar tending toward the high side of the reëntering angle.

In testimony whereof, we sign this specification in the presence of two witnesses.

BYRON A. LITCHFIELD.
LOUIS ZIMMERMANN.
